United States Patent

Des. 239,362

Patented Mar. 30, 1976

239,362

CORK SCREW

George Frederick Peterson, Boonton Township, N.J.,
assignor to Etamco Industries, Belleville, N.J.

Filed Sept. 16, 1974, Ser. No. 506,287

Term of patent 14 years

Int. Cl. D7—06

U.S. Cl. D8—42

FIG. 1

FIG. 2

FIG. 3

FIG. 4

FIG. 1 is a front elevational view of a cork screw showing my new design;

FIG. 2 is a side elevational view thereof;

FIG. 3 is a bottom plan view thereof; and

FIG. 4 is a top plan view thereof.

I claim:

The ornamental design for a cork screw, substantially as shown.
